UNITED STATES PATENT OFFICE.

JOSEPH ASHBY REAMS, OF RICHMOND, VIRGINIA, ASSIGNOR TO FULTON BRICK WORKS, OF RICHMOND, VIRGINIA, A CORPORATION OF VIRGINIA.

PROCESS AND APPARATUS FOR BURNING CLAY PRODUCTS.

Application filed December 2, 1926. Serial No. 152,156.

The object of this invention is to avoid injury to the product, reduce the cost of burning by economizing in fuel as well as time, and to avoid injury to the furnace by overheating, as more fully hereinafter set forth.

In the drawing—

Fig. 1 is a vertical transverse sectional view of a brick-kiln furnace constructed in accordance with my invention and illustrating the manner of operating the furnace during the preliminary, drying period;

Fig. 2 is a similar view showing the manner of operating the furnace during the final, burning period.

In carrying out my invention, I employ a furnace constructed as ordinarily, except that it is provided with an overhead stoking means consisting preferably of a passage 5 formed in the arch of the furnace adjacent the front wall of the furnace, this passage being provided with a cover 6 adapted to be held open or closed. I further provide the furnace with a supplemental air-supply passage 7 extending down through the arch, adjacent the back wall of the furnace, so as to deliver the air just over the flame-outlet 8 in the back-wall of the furnace, this outlet leading, of course, as usual to the burning-chamber in which the bricks or other products are arranged in the usual manner. This air-passage 7 is provided with a door 9 to enable the amount of air to be varied from time to time as conditions may require. The furnace is also provided with the usual grate 10, ventilating ash-pit-door 11, and shovel-stoker-door 12.

In carrying out my method, I fire the furnace in the usual manner, through the fire-door 12, during the preliminary, drying period, usually referred to as "water smoking." This water smoking generally requires several days. During this period, the door 6 is left open, and the door 9 is adjusted to deliver a supplemental supply of air to support combustion of the gases arising from the coal-bed. In addition, of course, such air as is needed is supplied through the ash-pit-door as well as the stoking-door. During this period, it is inevitable, as is well known, that a large amount of smoke will be produced. Heretofore this smoke has passed into the kiln, but in my present furnace I prevent it entering the kiln by shunting it out through the passage

5, into the atmosphere. I have found that by properly adjusting the draft, sufficient smoke will pass out through passage 5 during this stage of the operation to enable the flames to consume whatever smoke is carried into the kiln through the flame-passage 8, whereby I protect the product from soot deposits during this stage of the operation. Of course, this discharging of the smoke into the atmosphere involves a waste of fuel, but in practice I have found that the results of practicing my method render this waste negligible.

After the water smoking period is finished and the bricks or other products are thus thoroughly dried, I convert the furnace into a gas-producer by ceasing to fire through the door 12 and thereafter firing through the over-head passage 5, as shown in Fig. 2. The fuel is dumped down into the passage 5 as fast as it is consumed in the combustion-chamber. The fuel may be piled up in this passage to the top end thereof and allowed to gravitate as the fuel is consumed. During this gas-producing stage, I close the door 6 and open the door 9 to any extent that may be required to thoroughly consume the gases passing through the flame-passage 8, the quantity of air required being determined by observing the gases that flow out of the top of the kiln. In practice, I have observed that by closing, or practically closing, door 9, the gases arising from the kiln take on a smoky appearance showing lack of air to supply combustion. With door 9 properly adjusted, the gases arising from the kiln are practically invisible, showing practical consumption of smoke and gases. During this gas-producing stage, the flames in the fire-box are intensive enough to consume whatever smoke is produced if a sufficient supply of fresh air through passage 7 is provided for, and, therefore, in this final stage of burning also I protect the products against sootmaking smoke.

With the furnace as heretofore constructed, the water smoking stage requires a high degree of skill and care owing to the fact that there is no positive control of the furnace; also during this preliminary process the fire is slow and the gases contain a large amount of soot which passes to the clay products, lodging on them, thus not only injuring the products but having a tendency to choke the draft and thus retard the burn-

ing. All of these objections are done away with in practicing my present method.

In the carrying out of the second stage, several days are required, and in the furnaces now in use the fire must, at intervals, be allowed to die down for cleaning purposes; when this is done, cold air passes into the product and has an injurious effect upon the same. There is no necessity, in practicing my present method, for thus cleaning the furnace during this period, as the fuel is so completely consumed that only a fine ash remains. In this way, I not only avoid injury to the product, but improve its quality. This also reduces the time of burning materially.

I have found by experience that I so materially save in fuel in the producer stage of the burning that the slight waste suffered by allowing the smoke and the consumable gases to pass out through passage 8 during the preliminary stage is compensated for. I have also found that I can operate my method with a comparatively low temperature in the furnace, so that expansion of the furnace parts is not so great as with the old type of furnace, thus eliminating or reducing the expense of repairs due to fallen arches and crowns which intensive heat causes.

What I claim as new is:

1. A kiln furnace of the type having a fuel-grate, a shovel-stoking-door, and a rear flame-exit leading to the kiln, the top wall of said furnace being provided with a fuel-charging passage, this passage having a closure device adapted to be opened or closed, said fuel-charging passage being located ad-

acent the front wall of the furnace, a supplemental air-supply passage being provided at the rear of the furnace positioned to deliver air into the combustion-chamber at the inlet of the flame passage, this supplemental air-passage being provided with an adjustable closure device. 40

2. The method herein described of burning clay products consisting in diverting the smoke during the water smoking, preliminary stage of burning, away from the clay products and allowing only the flame to enter 50 the kiln chamber.

3. The method herein described of burning clay products consisting in diverting the smoke generated during the preliminary, water smoking stage of burning away from the kiln chamber, then during the final, burning period ceasing to divert the smoke and converting the furnace into a gas producer, whereby the entire products of combustion 55 are consumed. 60

4. The method herein described of burning clay products consisting in diverting the smoke generated during the preliminary, water smoking stage of burning away from the kiln chamber, then during the final, burning period ceasing to divert the smoke and converting the furnace into a gas producer, whereby the entire products of combustion 65 are consumed, a continuous supplemental supply of air being delivered into the furnace in position to mingle with the flames at the outlet of the furnace. 70

In testimony whereof I hereunto affix my signature.

JOSEPH ASHBY REAMS.
